UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,829, dated March 21, 1882.

Application filed February 11, 1882. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration 10 of figures hereinafter more fully described.

The accompanying photograph illustrates a face view of a carpet having my new design.

The ground *b* is composed of a number of figures various in shape, with irregular, zig-zag, right-lined borders, ornamented by various small figured work consisting of circular and fret work, short-lined, rectangular, diamond, and other geometric ornaments. These 15 figures are traversed by an irregular and scattered net-work of branches, *a a*, bearing various flower and other forms, forming an open design.

A is a large flower-figure with a heart-shaped center and pointed leaves at the base and sides, 20 and forming the crown. From the same stem projects to the left the two-leaf group *c*. Above, on the same stem, is *B*, with a diamond center, and surrounding petals, with a projecting blossom. Above *B* is the scattered flower group

d. To the right, on the same stem, is the large figure *C*, with heart-shaped center and surrounding pointed leaves, forming the crown. From *C* below projects a stem bearing the circular flower group *e*, with a leaf projecting to 25

the left above and a flowering twig to the left below. From the center of *e* projects to the right a stem bearing *D*, a large flower figure with heart-shaped center, surrounded by pointed radial leaves. Above *C* and on the same

30 stem is the small flower group *f*, from which projects a stem bearing the figure *E*, having a central bell-shaped flower surrounded by small pointed leaves. Above *f* is the large figure *F*, having a center of circular flowers surrounded

by radial pointed leaves. From *F* on the left 45 projects the flower figure *G*, somewhat similar to *E*, and above the circular flower *g*. Above *g* is the large figure *H*, having a shield-shaped center with surrounding pointed leaves and a projecting bud spray. From *F* on the right 50 projects the circular flower and flower spray *h* and the large figure *K*, having a central figure with large petals and pointed leaves around and above, and above *F* the scattered leaf-and-flower group *k*. Above *K* is the circular flower- 55 and-bud group *l*. Above *K* to the left is the large pointed petal and leaf flower *L*, (shown in part at each end of the photograph.) Connected with *L* on the right is the flower *M*, similar to *B*, with the circular flower group 60 above *m*. Connected with *L* on the left is the stained flower *N*, and above that the scattered circular flower-and-blossom clusters *n* and *o*.

O is a large pointed-leaf figure with a heart-shaped center. *P* is a smaller pointed-leaf figure. *p* and *q* are scattered groups of circular flowers and leaves. *Q* is a large pointed-leaf figure. *R* is a larger one, with diamond-shaped center. *S* is a smaller leaf figure above *O*. *r* 70 is a group of circular flowers.

I claim—

1. The design for carpets, consisting of the ground *b*, substantially as shown.
2. The design for carpets, consisting of the figures *A B C D E F G H K L M N O P Q R S c d e f g h k l m n o p q r* and stem *a*, with connected parts, substantially as shown.
3. The design for carpets, consisting of the figures *A B C D E F G H K L M N O P Q R S c d e f g h k l m n o p q r* and stem *a*, with connected parts and ground *b*, substantially as shown.

WINTHROP L. JACOBS.
